UNITED STATES PATENT OFFICE.

DAVID C. COBLE, OF YORK, PENNSYLVANIA, ASSIGNOR TO AMERICAN FOUNDRY EQUIPMENT COMPANY, OF NEW YORK, N. Y., A CORPORATION OF OHIO.

CORNER CONSTRUCTION FOR MOLDING FLASKS.

Application filed September 16, 1925. Serial No. 56,599.

The invention relates to molding flasks such as used in the making of molds for castings and the like. The better type of molding flask is preferably made from some 5 light non-corroding, long-wearing metal such as cast aluminum. It is not always practical to make a flask section in one piece, especially in larger sizes of flask. Therefore, it is the custom to make the several side 10 members of the flask separate, joining them together at the corners. It is necessary that the corner constructions be cheap, rugged and long wearing. They must not become loose or allow sand or moisture to get into 15 the cracks or joints formed at the corner. The corner must be as strong as the rest of the flask section and also as long wearing.

According to this invention a corner construction for a molding flask is provided in 20 which the adjoining ends of the side members are provided with diagonal projecting corner flanges which have connecting openings therein. The side members are connected together by casting a suitable metal 25 which is preferably softer than the material of the side members between the diagonal flanges and into the connecting openings to rigidly and securely connect the side members together. Furthermore, provision 30 is made so that should the corner become loose due to abnormal and unusual usage of the flask section, the connecting metal may be hammered or peened to tighten the joint 35 between the members.

Various other objects and advantages of the invention will be obvious from the following particular description of one form 40 of mechanism embodying the invention or from an inspection of the accompanying drawings; and the invention also consists in certain new and novel features of construction and combinations of parts hereinafter set forth and claimed.

In the accompanying drawings I have 45 shown for purpose of illustration one form of mechanism embodying the invention, in which

Fig. 1 is a plan view of a molding flask to which the invention is applied;

50 Fig. 2 is a fragmentary detail perspective of one end of one of the side members making up the flask;

Figs. 3 and 4 are fragmentary detail perspectives of the side member shown in Fig. 2 looking at opposite sides thereof;

55

Fig. 5 is an end elevation of one of the side members looking along the direction of the length thereof;

60

Fig. 6 is a perspective of a corner construction according to the invention;

65

Fig. 7 is a plan view of a corner construction according to the invention;

Fig. 8 is a section on the line 8—8 of Fig. 7; and

Fig. 9 is a section on the line 9—9 of Fig. 8.

In the following description and in the claims parts will be identified by specific names for convenience, but they are intended to be as generic in their application to similar parts as the art will permit.

Referring to Fig. 1 of the drawing, a section of a molding flask is shown with the invention applied thereto for purposes of illustration. It will be understood that 75 this construction may be applied to the lower or drag section, the upper or cope section, or to any flask section used in the molding art. The flask section may be rectangular in shape comprising four side members connected together by corner constructions according to the invention. Each side member has preferably an upwardly and inwardly extending side wall 1 with an outwardly extending top flange 2 and an outwardly extending bottom flange 3. The inclined side walls are provided to give the section a taper so that the section may be more readily removed from the mold after the molding 80 operation has been performed, as is clearly understood in the art. The upper surface of the top flange 2 and lower surface of the bottom flange 3 are preferably plane and flat to provide true meeting surfaces for adjacent sections as is well understood in 85 the art.

Since all corner constructions are the same it is only necessary for one to be described in detail. The side wall 1 of each pair of adjoining side members may end in a diagonal extending connecting flange 4 extending from the top flange 2 to the bottom flange 3. The adjacent connecting flanges 4 are provided preferably with concave op-

90

95

100

positely disposed faces 5, the other faces 6 of the diagonal flanges being plane. Each connecting flange 4 is provided with a plurality of connecting openings 7 extending between its faces, each connecting opening being provided with a reduced throat 8 extending substantially from the inner side face 10 of the opening near the concave face 5 to the outer side face 11 of the opening near the plane face as shown best in Fig. 9. Both the top and bottom faces and the side faces of each opening 7 are flared from said throat 8 on one side to the concave face 5 and on the other side to the plane face 6 of the diagonal flange 4 as clearly shown in the drawing. It will be readily understood that the connecting openings 7 are made in the shape shown for the purpose of forming an excellent interlocking joint between the side members and the connecting metal which is cast between them. The adjoining side members may be connected together by placing them at right angles with their concave faces 5 opposite and spaced from each other. Connecting metal, preferably some alloy of aluminum and preferably softer than the material of the side members is cast into the space between the concave faces 5 and into the connecting openings 7, suitable retaining means (not shown) being used for preventing the escape of the molten metal during the process of casting as will be clearly understood.

When the cast metal 12 becomes solid a rigid and strong joint is provided between the side members. It should be noted that the connecting openings 7 face sufficiently outwardly to allow hammering or peening of the connecting material 12 should occasion ever require to tighten the corner.

It will be seen that a corner construction according to the invention provides a joint between side members which is simple, cheap, rugged and easy to make. The joint will be at least as strong as the sections themselves and will last as long as the flask. There is little chance of the corner ever becoming loose because the cast metal when once set will always hold its shape and its interlocking engagement with the side members will hold the side members in the proper relation. However, if the side members ever become loose due for example, to abnormal or rough usage it can be easily seen that the connecting material 12 may be suitably peened and compressed against the faces of the side members and connecting openings 7 to make the corner as tight and rigid as it was when originally made.

While I have shown and described and have pointed out in the annexed claims certain novel features of the invention, it will be understood that various omissions, substitutions and changes in the forms and details of the device illustrated and in its op-

eration may be made by those skilled in the art without departing from the spirit of my invention.

Having described my invention, I claim:

1. Corner construction for a molding flask comprising side members each having a side wall ending in a projecting flange which has inner and outer faces, said projecting flanges being placed opposite each other in spaced relation, said projecting flanges each having connecting openings extending between its faces, a face of each of said openings flaring toward the outer face of the flange, and connecting metal located in space between said projecting flanges and in said connecting openings to rigidly connect said side members together. 70

2. Corner construction for a molding flask comprising side members each having a side wall ending in a projecting flange which has inner and outer faces, said projecting flanges being placed opposite each other in spaced relation, said projecting flanges each having a connecting opening extending between its inner and outer faces, a face of each of said openings flaring toward the outer face of the flange, and cast metal in the space between said projecting flanges and in said connecting openings to rigidly connect said side members together. 80

3. Corner construction for a molding flask comprising rectangularly arranged side members, each having a side wall ending in a diagonal flange which has inner and outer faces, said diagonal flanges being placed opposite each other in spaced relation, said diagonal flanges each having a plurality of connecting openings extending between its outer and inner faces, faces of said openings flaring toward the outer faces of said flanges, and connecting metal located in the space between said diagonal flanges and in said connecting openings to rigidly connect said side members together. 95

4. Corner construction for a molding flask comprising rectangularly arranged side members, each having a side wall ending in a diagonal flange which has inner and outer faces, said diagonal flanges being placed opposite each other in spaced relation, said diagonal flanges each having a plurality of connecting openings extending between its outer and inner faces, faces of said openings flaring toward the outer faces of said flanges, and cast metal in the space between said diagonal flanges and in said connecting openings to rigidly connect said side members together. 110

5. Corner construction for a molding flask comprising rectangularly arranged side members, each having an inclined side wall having top and bottom outwardly extending flanges, each side wall ending in a diagonal flange having a concave face and a flat face, said diagonal flanges being placed opposite 125

- each other with their concave faces in spaced relation, said diagonal flanges each having a plurality of connecting openings extending between its faces, each connecting opening 5 having a reduced throat extending substantially from the inner side face of the opening near said concave face to the outer side face near said flat face, the faces of said opening flaring from said throat on one side 10 to said concave face on the other side to said flat face, and cast metal in the space between said concave faces and into said connecting openings to rigidly connect said side members together.
- 15 6. A molding flask comprising a plurality of side members provided with openings therethrough, flat connecting members be-
- tween adjoining side members, and means for connecting said connecting members to said side members by interlocking engage- 20 ment in said openings.
7. A molding flask comprising a plurality of side members, each side member having a diagonal flange with a plurality of connecting openings therein, connecting members 25 between the diagonal flanges of adjoining side members for connecting said side members together, each connecting member comprising a flat body having connecting pro- 30 jections completely filling said connecting openings.

In testimony whereof I have hereunto set my hand.

DAVID C. COBLE.
